UNITED STATES PATENT OFFICE

ROBERT SCHLEMM, OF CHICAGO, ILLINOIS

TIME SWITCH

Application filed January 14, 1928. Serial No. 246,897.

This invention relates to time switches.

The object of the invention is to provide a spring time switch which may be set to function at different intervals of time, which is simple in construction, effective and dependable in operation and which may be manufactured at relatively small cost.

To effect the objects of the invention, a motor embodying my invention and improvements comprises the various features, combinations of features and details of construction hereinafter described and claimed.

In the accompanying drawings in which my invention is fully illustrated,

Figures 1 and 3 are front elevations of a time switch embodying my invention and improvements, shown as applied in use to a usual form of toaster, shown diagrammatically, respectively, showing the switch set and passive.

Figures 2 and 4 are sectional elevations, both taken substantially on the line 2-2 of Fig. 5, respectively showing the parts in set and passive positions.

Figure 5 is a sectional elevation taken substantially on the line 5-5 of Fig. 2.

Figure 6 is a sectional elevation taken, substantially, on the line 6-6 of Fig. 1; and

Figures 7 and 8 are enlarged detached, detail views.

In the accompanying drawings, in which I have, for purposes of clear and definite illustration, shown my improved time switch as applied in use to a bread toaster of what is known as the "flip-flop" type, A designates the toaster as a whole, which is indicated diagrammatically only, and V designates my improved time switch as a whole.

The toaster is of a usual type and can be purchased commercially and need not, therefore, be described in detail.

The operative parts of my improved time switch are mounted on a frame which preferably is constructed and arranged to form a casing, designated as a whole b. As shown, said casing comprises a base plate 1 of relatively heavy sheet brass or other suitable material, adapted to be secured to an end wall of the frame of the toaster A,

a cover plate 2 which may be stamped from relatively thin sheet metal, the edges of which conform to the shape of the base plate 1, and are adapted to fit over the same, and frame plates 3 and 4, of which the plate 3 is rigidly secured to the base plate 1 and the plate 4 is connected to the plate 3 by means of posts 5 and 6. As shown, the cover plate 2 is also supported by a post 7, which, as shown, forms an outer section of the post 6. Specifically, the construction of the frame b is immaterial and can readily be supplied by skilled mechanics and need not, therefore, be described in further detail.

The shafts 8, 8' to which the plates a of the toaster, which support the bread to be toasted, are secured, and which exemplify any rotatable member or members, extend through the base plate 1 of the casing b of the switch into the interior of said casing and secured thereto within said casing are segmental gears 9, 9' which are connected in train by intermediate idle gears 10, 10' which intermesh with each other and which respectively intermesh with the segmental gears 9, 9'. In the time controlled operation of my improved switch, the shafts 8, 8' are maintained normally in positions corresponding to turned-down positions of the toast supporting plates a by means presently described, and are adapted to be rotated manually to turn said toast supporting plates into operative position by mechanism as follows: Rotatably mounted on a stud 11 within the casing b is a sleeve 12 secured to which is a cam plate 13 and secured to the outer end of said sleeve which projects through the cover plate 2 of the casing of the switch is a lever 14 adapted for manual operation. Formed on the cam plate 13 is a cam surface 15 which is adapted to engage a stud 16 secured in the gear 10', the relation being such that when the lever 14 is depressed, the cam surface 15 will engage the stud 16 in a manner to impart rotation to the gear 10' and thus to the gear 10 and the segmental gears 9, 9' through an arc sufficient to raise the toast supporting plates a of the toaster from inoperative into operative positions.

Applied to the cam plate 13 is a spring 17

100

which connects said cam plate with a rigid part of the frame of the switch, said spring operating to retract said cam plate after the arm 14 has been manipulated to turn the 5 toast supporting plates *a* into operative position and released, said spring also operating to return said hand lever 14 to raised position.

In accordance with my invention, the 10 shafts 8, 8' are adapted to be turned into and maintained in positions corresponding to turned-down or inoperative positions of the toast supporting plates *a*, by means as follows:—

15 Rotatably mounted on a stud 18 secured in the base plate 1 of the frame of the switch is a plate 19 applied to which is a spring 20, one end of which is connected to a pin or stud 21 secured in said plate and the opposite end 20 of which is connected to a rigid part of the switch frame.

The only function of the spring 20 is to turn the toast supporting plates *a* into turned-down position. Thus the spring is 25 relatively light and can be made quite short, as shown, the ends thereof being connected to the stud 21 and to the fixed support by means of small wires.

Formed on the pivoted plate 19 is a shoulder 30 22 which is positioned so as to engage the stud 16 secured in the gear 10' when rotation is imparted to the plate 19 by the spring 20. Preferably, the reaction of said spring is only sufficient to impart rotation 35 to said gear 10' and associated parts, to turn the toast supporting plates *a* through the initial arcs of their movement from operative to inoperative positions—say 30 degrees—further movement of said plates to inoperative or turned-down positions being effected 40 by gravity.

With the described construction, when the cam 13 is operated to turn the toast supporting plates *a* into operative position, it is obvious 45 that it will be necessary to render the spring 20 inactive, as otherwise, said spring, acting on the plate 19, would return the toast supporting plates *a* to inoperative position as soon as the hand lever 14 was released, thus 50 permitting the spring 17 to retract the cam plate 13.

In accordance with my invention, the spring 20 is thus rendered inactive during the toasting period by means as follows:—

55 Formed on the plate 19 is a lug 23 which is positioned in the path of movement of the cam surface 15 on the cam plate 13 when said cam plate is turned pivotally by depression of the hand lever 14 to raise the toaster 60 plates *a*, the relative positions of the stud 21 and lug 23 being such that rotation of the plate 19 by the cam plate 13 will cause the line of tension of the spring 20 between its point of attachment to its fixed support on 65 the switch frame and to the stud 21, respec-

tively, to throw past its dead point, in which position it will be maintained against the tension of the spring 20 by engagement of a shoulder 24 on said plate with a stud 25 secured in fixed position in the base plate 1 of the switch frame. With the described construction, it is obvious that when the shoulder 24 on said plate is in contact with the stud 25, the spring 20, though under tension, will be inert and that the toast supporting plates *a* will remain in turned-up operative positions until the plate 19 is again rotated a sufficient distance in a reverse direction to cause the shoulder 22 thereon to approach the stud 16, and the line of tension of the spring 20 to again pass its dead point, whereupon said spring will again become active and will rotate said plate to effect engagement of the shoulder 22 thereon with the stud 16 secured in the gear 10', further rotation of said plate 80 by said spring imparting corresponding rotation to the gear 10' and associated parts to turn the toast supporting plates *a* through the initial arcs of their movement towards turned-down position. Fully turned-down 90 position of the plates *a* is defined by contact of a shoulder 26 on said plate 19 with the stud 25 which also limits rotation of the plate 19 and gear 10'.

The position of the plate 19 defined by 95 contact of the shoulder 26 with the stud 25 corresponds to designed operative position of the lug 23 relative to the actuating cam surface 15, when the toast supporting plates *a* are in turned-down inoperative positions. 100

As shown, when the plate 19 is in position corresponding to turned-up positions of the toaster plates *a*, the shoulder 22 is preferably positioned between the studs 21 and 16 and at an appreciable distance from the stud 16, so that when said plate is reversely rotated in operation to effect engagement of the shoulder 22 thereon with the stud 16, contact of said shoulder with said stud will not occur until the line of tension of the spring 20 makes an appreciable angle with a right line through the point of attachment of the spring 20 to the frame and the axis of the stud 18 on which the plate 19 is mounted, whereby the tension of the spring will act on the gear 10' with a correspondingly large leverage, thus insuring the designed operation of the parts.

In accordance with my invention, my improved switch embodies means for rotating the plate 19 to throw the line of tension of the spring 20 from inert to active position and to effect engagement of the shoulder 22 on said plate with the stud 16, as follows:—Mounted to rotate on the sleeve 12 is a gear 27 and rotatably mounted on the stud 11 which forms a bearing for the sleeve 12 is an arm 28, the underside of which is positioned in the path of movement of a stud 29 secured in the gear 27, when said gear is rotated in an anticlock-

wise direction, the position of the lug 29 relative to the lower edge of the arm 28 being such that said stud will engage the underside of the arm 28 substantially at the expiration of the toasting interval. As shown, the lower edge of the outer end of the arm 28 rests on the stud 25 and secured in the plate 19 is a stud or pin 30 which, when said plate 19 is in position corresponding to turned-up or operative position of the toaster plates *a*, is positioned as closely adjacent as practicable to a surface 31 formed adjacent to the end of the upper edge of said arm 28, in which position very slight pivotal movement of the arm 28 will be sufficient to rotate the plate 19 to throw the line of tension of the spring 20 from inert to active position.

As shown, the gear 27 meshes with a pinion 32 on the shaft of a usual form of clock spring motor, comprising a spring 33 which is enclosed in a barrel 34, opposite ends of said spring being secured to said motor shaft and barrel, respectively. Rotation of the shaft of the spring motor and also of the gear 27 is retarded by means of a usual form of fan governor, comprising a fan 35, a pinion secured to the shaft of which is connected in train with the pinion on the motor shaft.

As shown, also, the pinion 32 is mounted on the shaft of the spring motor so as to turn thereon and is adapted to be secured thereto by means of a pawl and ratchet gear, as shown at 36, Fig. 7.

In the preferable construction shown, the manner of applying the spring 20 to the plate 19 is such that the toast supporting plates *a* may be turned manually from operative to inoperative positions and vice versa, without affecting the "set" of said spring and plate, which will function in the contemplated manner at the end of the toasting period, if the spring 20 is under tension.

Preferably, also, my invention contemplates a construction whereby the spring 20 may be rendered altogether inoperative, thus adapting the toaster for manual operation only.

In accordance with my invention, this is effected in the following manner: The end of the wire which anchors said spring 20 to the frame of the device, instead of being attached directly to a rigid part of the frame of the device, is attached to what may be designated a bale 37 rotatably mounted by means of trunnions 38, 38' in bearings 39 formed in the ends of a yoke 40 secured in proper position to the frame *b*, the relation being such that when the bale is turned into position to bring the spring 20 under tension, the line of tension of said spring will pass on one side of the axis of rotation of the trunnions 38, 38' and a rigid part—as shown the lower edge of the intermediate portion 41 of the bale 37—will rest in contact with the

machine frame at a point to resist turning movement of said bale by said spring.

With the construction described, it is obvious that when the bale 37 is in the position shown in Figs. 2, 4 and 8, and the plate 19 is turned into the position shown in Fig. 4, in which the line of tension of the spring 20 has passed beyond the axis of rotation of said plate 19, it is obvious, that the shafts 8, 8', the segments 9, 9' secured thereto and the gears 10, 10' may be turned pivotally by hand to lower and raise the toast supporting plates *a* without in any way affecting the positions of the plate 19 and bale 37.

With the described construction it is also obvious that by turning the bale 37 in an anticlockwise direction to cause the line of tension of the spring 20 to pass the axis of rotation of the trunnions 38, 38', said spring 20 will become inert, and the toaster adapted for manual operation only, as the trip mechanism controlled by said plate 19 and spring 20 will be inoperative.

Obviously, also, said spring may again be rendered operative by turning the bale 37 in a clockwise direction to return it to its position shown in Figs. 2, 4 and 8.

As tripping of the throw-off plate 19 is effected by engagement of the stud 29 secured in the gear 27 with the trip-arm 28, it is obvious that the toasting interval or period will be substantially equal to the time required for the gear 27—actuated by the spring motor—to traverse an arc equal to that which separates the pin 29 from the trip arm 28, and that by providing means for turning said gear 27 in a clockwise direction through different arcs, the toasting interval or period may be varied within designed limits.

In accordance with my invention, the toasting interval or period is controlled by means as follows:—Pivoted upon the sleeve 12 adjacent to the gear 27 is a lever arm 42 formed on one end of which is a lug 43 adapted to engage the teeth of said gear, the end of said lever arm 42 at the opposite side of the sleeve 12 from said lug 43 comprising a portion 44 which diverges from the face of the gear 27 and the outer end of which projects through a circular slot 45 formed in the cover plate 2 of the motor frame, the outer end 46 of which is positioned, normally, at a suitable distance from the adjacent side of the cover plate 2, to permit rocking movement of the lever arm 42 about its point of divergence from the gear 27, as a fulcrum, sufficient to effect disengagement of the lug 43 on said lever arm from the teeth of the gear 27. Said lever arm 42 is maintained yieldingly in position corresponding to engagement of the lug 43 thereon with a tooth of the gear 27 by a coiled spring 47 inserted between said lever arm and the outer wall of the cover plate 2. The hole or opening in said lever arm, which re-

ceives the sleeve 12, is made sufficiently large to permit contemplated rocking movement of said lever arm in operation. The slot 45 through which the end 46 of the lever arm 42 projects is made of a length somewhat greater than the maximum arc which the gear 27 will traverse under the influence of the motor spring 33 as retarded by the fan governor 35, during the maximum interval that the toaster plates *a* are to remain in turned-up position.

10 Rotation of the gear 27 to provide an arc of desired length between the stud 29 and the underside of the trip arm 28 is effected by means of the cam plate 13, a shoulder or surface 48 on which is adapted to engage the lug 43 on the lever arm, when said cam is turned by depression of the operating lever 14. Thus, by manipulating the lever arm 42 to effect engagement of the lug 43 with the proper tooth of the gear 27, it is obvious that any desired toasting period or interval may be obtained between designed maximum and minimum periods.

I claim:

1. In apparatus of the type specified, the combination of an actuated member supported so as to be rotatable in opposite directions, power actuated means adapted for turning said member in one direction, and means comprising a single manually operable lever and a cam secured thereto so as to turn therewith, for turning said actuated member against the force of said power actuated means, and for subjecting said power actuated means to and securing it under operating tension, time-controlled tripping means for freeing said power actuated means when under tension, and means for setting said tripping means which also comprises said manually operable lever and cam.

2. Apparatus as specified in claim 1, in which the means connecting the common operating lever and cam with the actuated member comprises a gear secured to said actuated member, a normally idle rotatable gear which intermeshes therewith, and a projection on said gear adapted for engagement by an actuating surface of said cam.

3. Apparatus as specified in claim 1, in which the means for subjecting the power actuated means to and for securing it under tension comprises a pivoted plate, a stop which limits turning movement of said plate, a spring which connects said plate with a fixed support, and a projection on said pivoted plate adapted for engagement by an actuating surface of the cam, the relation being such that rotation of said cam will turn said pivoted plate to subject the spring applied thereto to tension and to cause the line of tension of said spring to pass its dead point and to effect contact of a rigid part of said plate with the stop which limits its turning movement.

4. Apparatus as specified in claim 1, in

which the means for subjecting the power actuated means to and for securing it under tension comprises a pivoted plate, a stop which limits turning movement of said plate, a spring which connects said plate with a movably supported part, and means for limiting turning movement of said part, the relation being such that when said movably supported part is in one extreme position the spring applied to said plate may be brought into tension by turning movement of said plate, and such also that when said movably supported part is moved into another position said spring will be unaffected by turning movement of said pivoted plate, and a projection on said pivoted plate adapted for engagement by an actuating surface of the cam.

5. Apparatus as specified in claim 1, in which the time-controlled tripping means comprises a pivoted arm, a tripping member rotatably mounted in association with said pivoted arm, a projection on said tripping member adapted to engage said pivoted arm to turn the same, motor means applied to said rotatable tripping member, and means rendered operative by manipulation of the common operating lever and cam for turning said tripping member against the force of said motor.

6. Apparatus as specified in claim 1, in which the time-controlled tripping means comprises a pivoted arm, a tripping member rotatably mounted in association with said pivoted arm, a projection on said tripping member adapted to engage said pivoted arm to turn the same, motor means applied to said rotatable tripping member, means rendered operative by manipulation of the common operating lever and cam for turning said rotatable tripping member against the force of said clock-spring motor, and means for varying the length of the arc through which said tripping member will be turned.

7. Apparatus as specified in claim 1, in which the time-controlled tripping means comprises a pivoted arm, a tripping member rotatably mounted in association with said pivoted arm, a projection on said tripping member adapted to engage the pivoted arm to turn said arm, motor means applied to said rotatable tripping member, and means rendered operative by manipulation of the common operating lever and cam for turning said rotatable tripping member against the force of said motor means through an arc of desired length, comprising a projection on said rotatable tripping member adapted for engagement by a part of said cam.

8. Apparatus as specified in claim 1, in which the time-controlled tripping means comprises a pivoted arm, a tripping member rotatably mounted in association with said pivoted arm, a projection on said tripping member adapted to engage the pivoted arm to turn said arm, motor means applied to said

rotatable tripping member, means rendered operative by manipulation of the common operating lever and cam for turning said rotatable tripping member against the force of said clock-spring motor through an arc of desired length, comprising an adjustable projection on said pivoted tripping member adapted for engagement by a part of said cam, and means for securing said projection on said tripping member in adjusted position.

9. Apparatus as specified in claim 1, in which the time-controlled tripping means comprises a pivoted arm, a rotatable tripping member, a projection on said tripping member adapted to engage the pivoted arm to turn said arm, motor means applied to said pivoted tripping member, means rendered operative by manipulation of the common operating lever and cam for turning said rotatable tripping member against the force of said motor through an arc of desired length, a projection on said rotatable tripping member adapted for engagement by a part of said cam, means for adjusting the position of said projection and for securing it in adjusted positions on said tripping member, comprising a pivoted lever arm supported adjacent said tripping member so as to permit rocking movement thereof, a lug on one end of said lever arm adapted to engage teeth formed in said tripping member, the end of said lever arm remote from said lug diverging from the face of said tripping member in such relation that pressure on the outer end thereof will impart rocking movement thereto to disengage the lug thereon from the teeth in said tripping member, and a spring applied to said lever arm adapted to maintain the same yieldingly in position to effect engagement of the projection thereon with the teeth in said tripping member.

10. Apparatus as specified in claim 1, in which the power actuated means applied to the actuated member and the means for securing said power actuated means under tension comprise a pivoted plate, a stop adapted to limit turning movement of said plate, a spring which connects said plate with a movably supported part, and means for limiting movement of said part, the relation being such that when said movably supported part is in one extreme position, the spring applied to said plate may be brought into tension by rotation of said plate, thus providing the motive force for turning the actuated member in one direction, and the relation being such also that when said movably supported part is moved into another position, said spring will be unaffected by turning movement of said pivoted plate, thus eliminating power operation of said actuated member.

11. In apparatus of the type specified, the combination of an actuated member movable in different directions, power actuated means

adapted for moving said member in one direction, means comprising a single manually operable lever for moving said actuated member against the force of said power actuated means, and for subjecting said power actuated means to and securing it under operating tension, adjustable time-controlled means for tripping said power actuated means when under tension, and means for setting said tripping means which also comprises said manually operable lever, the relation being such that during the interval for which the time-controlled tripping means is set, the actuated member may be moved in different directions without tripping the power actuated means.

12. Apparatus as specified in claim 11, in which the operating lever always executes a stroke of substantially uniform length regardless of variations in the timing, and the time-controlled tripping means comprises an adjustable member through which the operating lever acts to set said tripping means, the relation being such that said tripping means will be set during the final portion of the stroke of the operating lever.

In witness that I claim the foregoing as my invention, I affix my signature this 23 day of December, A. D. 1927.

ROBERT SCHLEMM.
